BRUSH MACHINE

William D. Lipps, Frederick, Md., assignor to Ox
Fibre Brush Company, Inc., New York, N. Y., a
corporation of Delaware

Application March 13, 1936, Serial No. 68,683

26. Claims. (Cl. 300—5)

This invention relates to brush machines, and particularly machines of the type illustrated in my Letters Patent of the United States No. 1,654,655, dated January 3, 1928, wherein brush blocks are bored and wisps of fiber or bristles are successively removed from a source of bristle supply and transferred to a station where each succeeding wisp is doubled on itself, seated in a hole of a brush block, and therein fastened by means of a wire staple that is formed by the machine and is associated with the wisp before their insertion in the brush block.

The object of my invention is to improve machines of the type referred to in various particulars hereinafter pointed out, whereby, amongst other important results, a more rapid and economical operation of the machine than formerly, with correspondingly increased production, is attained.

20 The invention comprises novel features of construction and combinations of parts, which in the preferred form of embodiment of the invention, will be hereinafter described, and the scope of the invention expressed in the appended 25 claims.

In the annexed drawings—

Figure 1 is a side elevation of a brush machine embodying my invention, the parts being shown in their relative positions when a wisp of fibers or bristles has been carried to the path of the inserting plunger and embraced by a reciprocating guide element preparatory to the raising of the wisp and the association of a staple therewith.

Fig. 2 is an elevation of the opposite side of the machine.

Fig. 3 is a front elevation of the machine.

Fig. 4 is a rear elevation of the main driving mechanism and adjuncts shown in the upper part of Fig. 1.

40 Fig. 5 is a horizontal section through the lower part of the machine in a plane directly above the pattern wheels and through the standards for the block supporting tables, as on the line 5—5 of Fig. 1.

45 Fig. 6 is a horizontal section in a plane between the said standards and the block-supporting tables, as on the line 6—6 of Fig. 1.

Fig. 7 is a transverse vertical section, as on the line 7—7 of Fig. 6.

50 Fig. 8 is a longitudinal vertical section, as on the line 8—8 of Fig. 6.

Fig. 9 is a perspective view of cam, lever and link connections for controlling the transverse rocking movements of the block supporting table.

55 Fig. 10 is a longitudinal vertical section, as on

the line 10—10 of Fig. 4, showing the centering mechanism for the brush tables.

Fig. 11 is a similar section, as on the line 11—11 of Fig. 4, showing the mechanism for operating the block boring tool.

Fig. 12 is a similar section, as on the line 12—12 of Fig. 3, showing the magazine, the wisp transfer head, the wisp carrier and the tufting, stapling and associated mechanisms, said transfer head being represented at the end of its receiving 10 stroke, and a wisp of bristles positioned by the carrier as in Fig. 1.

Fig. 13 is a similar section, but showing the transfer head at the end of its delivery stroke and positioned in the carrier, the inserting 15 plunger being in its down or inserting position.

Fig. 14 is a perspective view of the wisp transfer head, and adjuncts.

Fig. 15 is a similar view of the body of the magazine.

Fig. 16 is a similar view of the bristle evener and bristle feeder as removed from the magazine.

Fig. 17 is a horizontal section, as on the line 17—17 of Fig. 16, showing a cam and roll arrangement for actuating the bristle evener 25 currently with the bristle feeder.

Fig. 18 is a longitudinal horizontal section, in a plane through the transfer head and the plunger slide, as on the line 18—18 of Fig. 12.

Fig. 19 is a perspective view of the wisp carrier with a wisp thereon, the reciprocating guide element of the stapling and tufting mechanism being indicated in dotted lines in cooperative relation to said carrier.

Fig. 20 is a sectional detail of the wisp supporting structure of the wisp carrier, showing the abutment for opening the jaws of said structure.

Fig. 21 is an elevation of the reciprocating guide head and the slide to which it is connected.

Figs. 22 to 25, inclusive, are details showing successive positions of the wisp carrier and the guide head in relation to each other and to the fixed staple former.

Fig. 26 is a perspective view of the vertically 45 channeled supporting block for the fixed plunger guide and staple former.

Fig. 27 is an elevation partly in section of the reciprocating guide head and the fixed staple former, showing a staple engaged with the wisp 50 in the throat of the guide head, and also showing the wire cutting devices with the movable cutter member in raised position, and the wisp carrier in its initial return movement toward wisp-receiving position.

Fig. 28 is a horizontal section, as on the line 28—28 of Fig. 27.

Fig. 29 is a perspective view of the wire feeding and cutting devices, together with an orbitally 5 movable mandrel which co-acts therewith and with the fixed staple former to shape succeeding staples and position each staple in the path of the plunger.

Fig. 30 is a sectional rear elevation of the 10 wire feeding and cutting devices, the mandrel and associated plunger guide with its staple former, as on the line 30—30 of Fig. 18.

Fig. 31 is an enlarged view of the lower end of 15 the plunger guide constituting the staple former, showing the adjacent fixed member of the wire cutter, and also showing a staple as formed and positioned in the staple former.

Fig. 32 is a horizontal section, as on the line 32—32 of Fig. 31, but showing the movable cutter 20 member in co-operative relation to the fixed cutter member and the leading end of the staple wire as severed preparatory to its insertion in the staple former by the mandrel.

Fig. 33 is a transverse vertical section through 25 the wire feeding wheels and adjuncts.

Fig. 34 is a partial longitudinal vertical section, 30 as on the line 34—34 of Fig. 4, showing the mechanism for actuating the oscillating tuft shifting casing with which the guide head coacts.

Fig. 35 is a vertical section through the said 35 tuft casing actuating mechanism, as on the line 35—35 of Fig. 1.

Fig. 36 is a vertical section in a plane through 35 a pair of reciprocating rack bars included in the tuft casing actuating mechanism, as on the line 36—36 of Fig. 34.

Fig. 37 is a partial vertical section, as on the line 37—37 of Fig. 3, showing the tuft casing 40 actuating mechanism, including control means therefor, such casing being shown in vertical position at the brush block.

Referring to the drawings, 35 designates the main frame comprising a base 36, spaced parallel standards 37 rising therefrom, and a horizontal beam 38 connecting the upper ends of the standards. The main shaft 39 is journaled in bearings in rearwardly extending brackets 390 supported by the beam 38, which shaft has loose thereon a positively driven pulley 40 adapted to 50 be clutched to or unclutched from the shaft and other elements mounted thereon as will presently appear.

41 designates a lower transverse shaft which is journaled in bearings on a pair of spaced arms 55 42 extending rearwardly from a cross-bar 43 bolted to the standards 37 of the main frame. The shaft 41, which is intermittently driven through suitable connections with the main shaft, has fast thereon spaced apart wheels 44 and 45 60 to the former of which are affixed segmental pattern cams 46 and 47 and to the latter of which wheels are secured pattern cams 48. These cams determine the succeeding movements of the mechanism for controlling the various operative positions of the block supporting tables 49 and 50 in respect to boring and tuft inserting devices as hereinafter described.

In the present instance the shaft 41 has fast 70 thereon a spur wheel 51 in mesh with a pinion 52 fast on a short shaft 53 having its bearings in a suitably-disposed bracket 54 on the cross-bar 43. Fast on the shaft 53 is a ratchet wheel 55 with the teeth of which engages a pawl 56 on a rock-arm 57 loose on the shaft 53. This arm is pivotally connected by means of a rod 58 with the

arm 59 of a bell-crank which is fulcrumed on a bracket 60 at the frame beam 38. The other arm 61 of the bell crank has a roll 62 which is held by means of a suitably disposed spring 63 in operative contact with a cam 64 normally loose on the main shaft, which cam can be clutched at will to the power driven pulley 40 loose on the main shaft and which cam can also be automatically released from the pulley at predetermined intervals. (See Figs. 2, 4 and 5.) The contour of the cam 64 is such that when it is clutched to and driven by the pulley the bell crank is rapidly oscillated and intermittent rotary motion thereby transmitted to the shaft 53 through the link and pawl and ratchet connections, thence through the pinion 15 and spur wheel to the shaft and the pattern wheels. To prevent the overrunning of the pattern cams 46, 47 and 48 in their intermittent rotation, the shaft 53 is provided with a brake drum 65 embraced by brake arms 66. 20

The means for clutching the cam 64 to and releasing it from the pulley 40 is of the character disclosed in my prior Patent No. 1,654,655 and therefore it requires no detailed description herein. Suffice it to say that such means includes 25 a manually operative crank shaft 67 for actuating brake and clutch mechanism 68 in relation to the cam and the pulley in a manner to effect the starting or the stopping of the operating mechanism for the pattern wheels at the will of the attendant; which means also includes a toggle actuating cam lever 69 which is automatically actuated through link and lever connections 70 by a cam 71 on a wheel 72 fast on the intermittently movable shaft 41, so as to effect the stopping and the starting of the said pattern wheel 30 operating mechanism at determined intervals during the brush forming operation. Also located on the main shaft 39 in co-operative relation to the sleeve or hub of the cam 64 as described in said Patent No. 1,654,655, is a second clutch and brake mechanism 73 which is automatically actuated by a cam 74 on the wheel 72, through link and lever connections 75 to control the timed operation of the main shaft and therefore the operation of the boring and tufting devices, as well as the stopping of such devices while the pattern wheels continue their rotation and until they are manually or automatically stopped as previously mentioned. 50

The brush block supporting tables 49 and 50 have pairs of spaced depending legs 76 each of which is rockably supported on a transverse vertical frame 77, comprising spaced bars, by means of a pivot 78 extending longitudinally of the 55 table; the frame 77 being secured at its ends to upstanding arms 770 which are pivoted on horizontal axes 79 to two vertical slides 80 guided in fixed standards 81 rising from a pair of forwardly extending arms 82 on the cross-bar 43. (See Figs. 1, 2 and 5.) Thus the tables are movable longitudinally about the axes 79, transversely about the axes 78, and vertically in the guide standards 81 so as to enable the setting of the block tables in predetermined operative positions 60 in relation to the overhanging boring and tufting devices, respectively. 65

The pivots 78 of the legs 76 of the two tables 49 and 50 are pivotally coupled by lateral links 83 which are connected by means of retracting 70 springs 84 with a cross-rod 85 fixed to a stud 86 on one of the end members of the vertical frame 77, which spring connections thus tend to retract the links 83 toward one side of the machine and thereby resiliently to cant the block 75.

tables on their axes 78. (See Figs. 1, 2, 6, 7 and 8.)

The cams 48 on the wheel 45 are adapted through suitable connections to move the block tables transversely on the axes 78 against the action of the springs 84; the cams 47 on the wheel 44 are adapted to move the tables vertically, and the cams 46 on the latter wheel are adapted to move the tables longitudinally on the axes 79, the various movements being in timed relation to present the supported brush blocks (B) at determined intervals to the paths of the boring and tufting devices.

One feature of my invention resides in the cam actuated connections for moving the block tables back and forth transversely on the axes 78, as follows, reference being had to Figs. 1, 2, 5 and 9:

A transverse shaft 87 is slidably mounted in guide brackets 82 on the forward arms 82 of the cross-bar 43, one end of which shaft 87 has attached thereto a strap 89 that passes about a pulley 90 at one side of the frame standard 37 and supports a pendant weight 91 tending to retract the shaft 87 longitudinally in one direction. This shaft has pivoted thereto one end of a parallel link 92 the other end of which has a pin and slot connection with one arm 93 of a bell crank which is fulcrumed, as at 94, on the cross-bar 43 of the main frame, the other arm 95 of the bell crank being pivoted at 96 to one end of a stabilizing arm 97 having a lateral roll 98 which is held in operative relation to the cams 48 by the retractive force of the weight 91 on the shaft 87. The opposite end of the arm 97 is bifurcated 30 and bears a roll 100 fitted in a cam slot 101 in a horizontal plate 102 which is fastened to the adjacent rearwardly extending arm 42 of the cross-bar 43. Hence during the rotation of the cams 43 the roll 98 and the adjacent end of the arm 97 are radially moved in a manner to swing the bell crank and impart variable longitudinal movements to the sliding shaft 87 in one direction against the action of the weight, and also to permit the intermittent retraction of such shaft 40 in the opposite or return direction by the action of the weight. The contour of the cam slot is such as to coordinate the actions of the arm 97 and the bell-crank arm 95 during the varying movements of the arm 97, and thus ensure the 50 radial movement of the roll 98 in relation to the cam wheel.

Loose on the shaft 87, but movable longitudinally therewith, is a forwardly and downwardly inclined arm 103 to the outer end of which is pivotally connected the lower end of an upstanding shifter arm 104 having at its upper end a rounded projection 105 which is seated in a corresponding socket 106 formed in the central expanded portion 107 of a cross-bar 108 connecting the lateral links 83 which couple the legs 76 of the block supporting tables 49 and 50. The springs 84 maintain the socketed bar 108 in constant contact with the projection 105 of the shifter arm 104, and hence as the shaft 87 is variously moved lengthwise through its connections with the cams 48 the links 83 are correspondingly lengthwise shifted; thus simultaneously moving the tables on their axes 78 in a manner to present the brush blocks in determined angular relations to the actions of the boring and tufting devices.

In the present instance two sockets 106, one spaced above the other, are formed in the expanded portion of the bar 108 so that the projection 105 on the shifter arm 104 can be seated in either socket, and accordingly enable the varia-

tion of the vertical position of the frame 77 in relation to the boring and tuft inserting devices so as to adapt the block tables for different tuft lengths as the particular style of brush may require. The socketed bar 108 is shown in Fig. 7 in full lines as detachably secured by bolts 109 to the tops of the links 83. In order to provide for other vertical variations of the frame 77 the socketed bar may be detached and reversely secured to the bottoms of the links 83 as indicated in dotted lines in Fig. 7, thus enabling further vertical positions of the sockets of the bar 108 to be had, as occasion may require.

The cam actuated means herein illustrated for moving the block tables 49 and 50 longitudinally on the axes 79, is as follows, reference being had to Figs. 1, 2 and 5:

A horizontal rock-shaft 110 has its bearings in brackets 111 on the cross-bar 43 of the main frame adjacent the pattern wheels, which shaft 20 has affixed thereto an arm 112 having a roll 113 which is held in operative relation to the pattern cams 46 by means of a weighted arm 114 on the shaft. Rising from this shaft are two levers 115, the upper ends of which are connected by links 25 116 to the upper ends of the upstanding side arms 77 of the frame 77. Stout retracting springs 117 connect the links 116 to rearwardly extending bars 118 secured to the standards of the main frame and serve to retract the frame 77 against 30 the action of the cams 46 on the wheel 44, which cams are of such formation as to effect, in conjunction with the action of the springs 117, the requisite longitudinal movements of the frame 77 and the block tables to present the blocks in 35 proper relation to the boring and tufting devices.

The cams 47 on the wheel 44 control the vertical movements of the tables to preserve at all times, irrespective of the longitudinal and lateral movements of the tables, the same distance between the boring and tufting devices and the portions of the respective blocks vertically beneath them. These cams 47 act upon a roll 119 on a lever arm 120 extending rearwardly from a rock-shaft 121 journaled in brackets 122 on the base of the main frame. Extending forwardly from the rock shaft 121 are a pair of spaced arms 123 which are connected by links 124 with a transverse tie bar 125 slidably mounted at its ends in vertical guides 126 secured to the standards of the main frame. The tie-bar 125 connects the depending ends of the vertically movable guide bars 80 for the frame 77, and hence the determined actuation of the lever arm 120 by the cams 47 effects the requisite vertical movements of the 50 frame 77 for the purpose mentioned. (See Figs. 1, 2, 3 and 5.)

The mechanisms just described for longitudinally and vertically moving the tables are substantially the same in construction and operation 60 as those described in the Young Patent No. 664,989, dated January 1, 1901.

Simple and efficient means to ensure the accurate positioning of the tables and the blocks thereon in respect to the paths of the boring and tufting devices at the end of each longitudinal and transverse movement of the tables, is as follows, reference being had to Figs. 2, 4 and 10:

Pivoted to the block table supporting frame 77, at a point midway between the depending legs 70 76 of the respective tables 49 and 50, are the depending legs 127 of a table 128 upon which a flat plate 129 is supported in substantially the same plane as and in parallel relation to the tops of the brush blocks. The plate 129 has formed there-

in rows of perforations 130 corresponding in number, position and angularity with the holes to be bored in the brush block. The pivots of the legs 127 of the table 128 are coupled to the links 83 similarly to the pivots of the legs 76 of the block tables 49 and 50, and hence the three tables are simultaneously and correspondingly moved on their transverse axes by actuation of the links 83, as hereinbefore described.

10 At the end of each movement of the plate 129 one of the holes therein is in vertical alignment with an overhanging vertically reciprocating centering pin 131 which is at once snugly entered in the hole preparatory to the boring and tuft setting operations on the blocks, thus ensuring the accurate positioning of the respective blocks in relation to the boring and tuft setting devices. The centering pin 131 depends from a vertical spindle 132 which is slidably mounted in guides 133 on a bracket 134 fixed to the front of the cross-beam 38 of the main frame. The spindle 132 is connected by a pair of links 135 to one arm 136 of a lever which is fulcrumed on the bracket 134. (See Fig. 10.) The other arm 137 of the lever has a roll 138 which is held (by gravity) in contact with a suitable cam 139 fast on a short shaft 140 mounted below the main shaft in a bracket 141 fixed to the rear of the cross-beam 38. The shaft 140 has fixed thereon a sprocket wheel 142 which is connected with and driven from a similar wheel 143 on the main shaft 39 by a chain 144. The contour of the cam 139 is such that in each rotation thereof the spindle is lowered and raised in timed relation to the centering plate and the block supporting tables.

15 The boring mechanism herein shown comprises a boring tool 145 at the foot of a vertical spindle 146 which is rotatably and slidably mounted in a guide bracket 147 fixed to the front of the cross-beam 38 of the main frame, such spindle being independently driven by a suitably-supported electric motor 148. The spindle 146 is rotatably connected, as usual, to one arm 149 of a rock lever having its fulcrum in the bracket 147, the other arm of the lever having a roll 150 which is operatively fitted in the groove of a suitable cam 151 fast on the main shaft 39. The contour of the cam groove is such as to effect the vertical oscillation of the lever and the resulting reciprocation of the rotating spindle and its boring tool in timed relation to the block feeding tables. (See Figs. 2, 4 and 11.)

20 The fiber supply means herein illustrated comprises a magazine 152 which is supported by a bracket 153 on a forward extension 154 of a supplemental frame structure 155 on the cross-beam 38 of the main frame. This magazine is open at one side and is formed at its lower end with a throat portion 156 from which determined quantities of fiber (each quantity sufficient to form a tuft) are successively removed by a transfer device (T) and thereby delivered to a wisp carrier (C) which, in turn, presents the wisp to the respective actions of co-operatively related tuft forming and setting mechanisms as will be hereinbefore described.

25 In order to ensure the uniform and orderly feeding of the fibers through the throat of the magazine into the transfer device, means are provided for evening the exposed ends of the fibers at the throat, and for pressing the fibers toward and into the transfer device. (See Figs. 12, 13, 15, 16, 17 and 18.)

30 The fiber evening means comprises a vertically-disposed plate 157 which is arranged at the

lower part of the open side of the magazine adjacent the throat so as to be vibratable against the exposed ends of the fibers. This plate is adjustably connected by means of a rod 158 with the bifurcated lower end of a depending arm 159 which is movable in a path longitudinally of the fibers. The arm 159 has thereon a bracket 160 which bears a roll 161, the arm being pivoted at its upper end, as at 162, to the front wall of the frame extension 154 which supports the magazine. A retracting spring 163 secured to the bracket 160 and front wall of the extension 154 maintains the roll 161 in contact with a beveled cam plate 164 on an adjacent pendant arm 165 which is movable toward and from the magazine. Thus the cam 164, in conjunction with the spring 163, actuates the arm 159 in a manner to vibrate the plate 157 against the exposed ends of the fibers in the magazine for the purpose mentioned.

35 The arm 165 is fixed at its upper end to one end of a rock-shaft 166 having its bearings in a bracket 167 on the extension 154, the other end of the shaft having a depending arm 168 which is resiliently connected to such extension by means of a spring 169. Thus the arm 165 is normally urged toward the throat of the magazine. The shaft 166 has an upstanding arm 170 which is connected by means of a rod 171 with a rock-arm 172 included in connections hereinafter described for operating the transfer device. One end of the rod 171 is pivoted to the arm 172 and the opposite end extends loosely through a guide rocker 173 on the arm 170, a cushioning spring 174 being interposed between the rocker and a nut 175 on the projecting threaded end of the rod. The lower end of the arm 165 has fixed thereto a pair of parallel rearwardly extending blades 176 having free vertical edges 177 from the tops of which the upper edges of the blades 40 are inclined downwardly and forwardly, as at 178. The free ends of the blades 176 are movable through slots 179 in the inclined bottom 180 of the magazine by the vibrating arm 165, and hence the vertical edges of the blades in their inward 45 strokes press the lowermost fibers toward the transfer device, and the inclined upper edges of the blades in their return strokes move freely away from the superposed fibers.

50 The fiber transfer means hereinbefore referred to consists of an oscillatory head of the general character disclosed in my previous Patent No. 1,888,352, dated November 22, 1932, which head in the present machine is rocked in timed relation to the wisp supporting carrier through an arc of 90° between the throat of the magazine and the carrier. The transfer head comprises a segmental member 181 fixed to and supported by radial arms 182 fast on one end of a rock shaft 183 having its bearings in brackets 184 on the lower forward part of the frame structure 155. On the opposite end of the shaft 183 is fixed a sector gear 185 in mesh with a similar gear 186 loose on a stud shaft 187 supported by the frame extension 154. The sector gear 186 has an arm 188 which is connected by a link 189 to the rock-arm 172 previously referred to. This arm is fast on one end of a transverse rock-shaft 190 having its bearings in brackets 191 on the cross-beam 38 of the main frame. On the opposite end of the shaft 190 is a rearwardly extending arm 192 having a roll 193 operatively fitted in the groove of a cam 194 fast on the main shaft 39, the contour of the groove being such that in an interval in each rotation of the main shaft the connec-

tions between the cam and the sector arm 188 are actuated to effect the oscillation of the transfer head at the throat of the magazine.

The segmental member 181 has a suitably-disposed peripheral slot 195 therein effective to receive a wisp of fibers from the throat of the magazine when the segment is at the top of its stroke, and then to carry the wisp down to its position for delivery to the wisp carrier. The 10 segment has pivotally mounted thereon, as at 196, a pair of curved stripper arms 197 which are movable radially in respect to the slot, which arms are swung inward to open the slot for the reception of the wisp at the throat of the magazine, and is subsequently swung outward to deliver the wisp to the wisp carrier. The pivoted 15 ends of the strippers are formed with crank arms 198 connected by a cross-pin 199 extending through an arcuate slot 200 in an expanded arm 201 of a small lever which is pivoted between the crank arms, the other arm 202 of the lever being provided with a roll 203 and being also connected by a spring 204 with one of the segment supporting arms 182. The roll 203 is held by the 20 action of the spring in contact with a stationary cam 205 on an arm 206 having a hub 207 encircling a sleeve 99 and fixed thereto. The sleeve is fixed at its ends in the brackets 184 in which the rock shaft 183 is journaled, which shaft extends freely through the sleeve. (Figs. 14 and 18.) The contour of the cam face is such that during each stroke of the segment, the lever 202 is actuated to effect the determined opening and closing movements of the strippers in respect to 25 the wisp receiving slot of the transfer head. A curved guard plate 208 to confine the wisp of fibers in the slot 195 during the delivery stroke of the transfer head is resiliently supported adjacent the periphery of the segment 181.

40 In the present instance this plate has a depending pin 209 which is slideable in perforated guide ears 210 on a forwardly extending bar 211 bolted to a depending housing 212 on the frame structure 155, and which pin is maintained yieldingly in raised position by a suitably-disposed compression spring 213. (See Figs. 12, 13 and 14.)

The wisp carrier hereinbefore referred to comprises a slide 214 fitted in a guide 215 fixed to the housing 212 on the frame structure 155, which guide is inclined upwardly and rearwardly from a position adjacent the lower path of a vertically reciprocating plunger 217 included in tuft forming and setting mechanism. The slide 214 has secured thereto a similarly inclined plate member 218 terminating in a forwardly extending open wisp supporting structure. This structure comprises a side wall 219 extending from the member 218 and a side wall 220 parallel with the wall 219 and suitably spaced therefrom by means of a cross-piece 221. The two walls have formed at their rearward ends upstanding jaws 222 with which co-act complementary jaws 223 pivoted on the respective walls, as at 224. The 50 depending portions of the pivoted jaws are jointed, as at 225, to the parallel limbs of a yoke 226 below the forward portion of the cross-piece 221, which yoke is normally retracted by the action thereagainst of a spring 227 which is seated in a socket 228 in the cross-piece 221. A retaining pin or screw 229 in the cross-piece of the yoke is encircled by the outer projecting coils of the spring.

75 By the construction just described it will be

seen that when the slide 214 is longitudinally reciprocated in the inclined guide 215, the wisp supporting structure with its normally closed jaws is moved in an oblique path intersecting the vertical path of the inserting plunger 217. As such structure approaches its lowermost position the yoke 226 impinges against an abutment piece 226 fixed on the forwardly extending bar 211 on the depending housing 212, which yoke is thus moved slightly rearward against the action of 10 the spring in a manner to swing the pivoted jaws 223 to open position; and in the initial upward movement of the wisp carrier the yoke, leaving the abutment, resumes its normal forward or jaw closing position. (See Figs. 12, 13, 15 19 and 20.)

The means herein illustrated for reciprocating the wisp carrier includes a suitable cam 230 on the driven shaft 140, the groove of which cam receives a roll 231 on the shorter arm 233 of a 20 bell crank which is pivoted, as at 234, on the beam 38 of the main frame. The other arm 235 of the bell crank has jointed thereto a link 236 which is pivotally connected with the slide 214 of the wisp carrier.

When the wisp carrier is in its lowermost position, as seen in Fig. 13, with its jaws open, as previously mentioned, a wisp (F) of fibers or bristles is delivered by the transfer head to and upon the spaced side walls 219 and 220 of the 30 wisp supporting structure and in the space between the open jaws, which jaws in the initial backward movement of the carrier are caused to grasp the wisp and as the movement continues the wisp is lifted in an inclined plane to a position where it is sustained horizontally and with its midportion intersecting the path of the inserting plunger 217, as seen in Figs. 12 and 22.

The plunger 217, which is included in the tuft forming and inserting mechanism herein illustrated, is preferably polygonal in cross-section and is vertically reciprocated in timed relation to the block feeding tables. (See Figs. 1, 12, 13, and 18.) The upper end of this plunger is fixed to a slide 237 mounted in a vertical guideway 238 formed in the supplemental frame structure 155. The body of the plunger 217 is slideable in longitudinal grooves in a fixed block 239 having a bifurcated lower end 240 constituting a staple former through which the plunger is freely movable. The block 239 is preferably composed of two mating sections (Figs. 30 and 31) which are fixed in a vertically channeled block 241 (Fig. 26) fastened to the foot of the frame structure 155. The slide 237 is connected by means of a link 242 with one arm 243 of a lever which is fulcrumed on the frame structure 155, the other arm 244 being pivotally connected by means of a link 245 to the plain face of a cam 246 on the main shaft 39. Thus during the operation of the main shaft 60 the slide 237 and therewith the plunger 217 are vertically reciprocated, the down stroke of the plunger being such that its lower end enters the opposing hole of the underlying bored brush block. When the plunger is at the limit of its 65 upper stroke its acting end is within the block 239 and above the bifurcated staple former of the latter. The grooved inner walls of the spaced members of the staple former receive and support the depending legs of a staple which is formed 70 and seated between such members, as will presently appear.

Fitted in the vertical guide 238, directly above the bifurcated staple former, is a reciprocative slide 247 to which is affixed, laterally of the ver- 75

tical medial portion of the body of the slide, a depending bar 248 carrying a vertically-disposed elongated guide head 249 positioned below and in vertical alignment centrally with the staple former. The upper and lower portions of the guide head are tapered, as at 250 and 251, respectively, the tapering portions being slotted longitudinally and being in direct communication with a longitudinal tuft-forming passage 252 formed therebetween in the body of the guide head.

In the present instance the guide head 249 comprises two mating sections whereof the inner vertical edges are longitudinally grooved, as at 253, correspondingly with the body of the fixed guide block 239 so as to receive and guide the reciprocating plunger. The sections are held in spaced relation by longitudinally grooved lateral plates 254 secured thereto, one of which plates 20 has an extension 255 which is fastened to the lower end of the bar 248. These plates are medially channeled longitudinally, as at 256, to afford expanded side walls for the space between the parallel sections of the guide head 249, thus providing the tuft-forming passage 252, while the up-projecting slotted portion of the head affords a throat or pocket 251 for the reception and support of a transversely disposed wisp of fibers directly above the mouth of the passage 30 and also for the reception and guidance of the staple and the plunger.

Fixed to the outer face of the guide head 249 is an upstanding finger 258 which is so disposed that when the guide head is in position to receive a wisp borne by the carrier to the path of the plunger, the finger serves as an abutment for the wisp.

The slide 247 is pivotally connected by means of a link 259 with one arm 260 of a lever which 40 is fulcrumed on the frame structure 155, the other arm 261 of the lever bearing a roll 262 which is operatively fitted in the groove 263 of the cam 246, the contour of which groove is such that the guide head 249 is moved in timed relation to the plunger. (See Figs. 1, 12, 13, 19, 22 to 25, inclusive, and 27.)

The co-operative relation of the parts just described is such that as the wisp carrier reaches the limit of its rearward stroke the upstanding throat portion of the guide head is raised to a position under and near the wisp which is borne by the carrier, as seen in Fig. 22, whereupon the guide head continues and completes its upward travel to a position immediately under the bifurcated staple former, as seen in Figs. 23, 24 and 25. Within this staple former there has been previously formed and positioned directly under the elevated plunger 217 a staple (S) having depending prongs, as will be hereinafter described.

60 The plunger descends and initially forces the opposing staple directly from the staple former into the throat 251 of the guide head 249 and with the legs of the staple seated in the plunger guide grooves of the throat, as seen in Figs. 25 and 27. In the continued descent of the plunger the staple is caused to straddle the opposing wisp, F, and carry it bodily down into and through the elongated passage 252 of the guide head, the portions of the wisp on the respective sides of the staple thus bearing against the wall plates 254 of the passage 252 and being thereby folded up in tuft-form. Concurrently with the descent of the plunger, after the engagement of the staple with the wisp, the guide head 249 is moved downward toward and in close relation

to the brush block, whereupon in the final descent of the plunger the tuft and associated staple are entered in the hole of the brush block and the staple is driven into the bottom of the hole, thereby securely fastening the base of the tuft to the 5 brush block.

It is to be noted that the wisp carrier and the transfer head are movable toward and from each other in such timed relation that the transfer head is positioned to receive a wisp of fibers 10 from the supply magazine while the carrier is presenting to the path of the guide head 249 and the inserting plunger, the last preceding wisp which was delivered to the carrier by the transfer head, thus effecting a rapid disposition of the 15 succeeding wisps in the active path of the plunger and enabling corresponding speed of the tuft forming and setting operation.

The means herein illustrated whereby staples are successively formed and positioned in the 20 staple former 240 in timed relation to the reciprocations of the plunger, the wisp carrier and the guide head are as follows, reference being had to Figs. 12, 13, 27 to 32, inclusive, 34 and 35:

A short mandrel 264 of appropriate form is 25 movable in a vertical orbital path traversing the vertical slot of the staple former. This mandrel projects endwise from a bar 265 which is pivoted, at 266, between a pair of depending lugs 267 on the foot 268 of a pendant lever 269, whereof the upper end is slotted as at 270 and slidably fulcrumed on a pin 271 fixed to a bracket 272 on the frame structure 155. The bar 265 has a slight vertical rocking motion, and is maintained with its acting or mandrel end resiliently raised by 30 means of a spring 367 which is interposed between the bar and the heel of the lever foot 268. The lower forward portion of the lever is pivotally connected to a crank 368 on one end of a short longitudinal shaft 369 having its bearings 40 in a bracket 370 on one side of the frame structure 155. Fast on the other end of the shaft 369 is a bevel gear 371 in mesh with a similar gear 372 on a short transverse shaft 273 having its bearings in the bracket 370 and also in a bracket 45 274 also mounted on the frame structure 155. Fast on the shaft 273 is a sprocket wheel 275 which is connected by means of a chain 276 with a similar wheel 277 on the driven shaft 140 previously referred to. Hence the shaft 273 is continuously rotated and the crank 368 thereon actuates the lever 269 in a manner to impart a vertical orbital movement to the foot of the lever and the associated mandrel supporting bar 265.

65 Adjacent one side of the mandrel 264 is a vertically movable cutter head 278 formed with a beveled vertical face 279. This head is formed on the expanded free end of a horizontal lever 280 pivotally mounted at 281 in a yoke member 282 on an arm 283 which is resiliently supported 60 by a suitable spring 284 secured thereto and to a pin 285 on the beam 38 of the main frame.

The beveled cutter head 278 and the adjacent end of the lever 280 are longitudinally perforated, as at 286, for the passage therethrough of a longitudinal strand of wire (W) which is threaded through a suitable guide tube 287 carried by the lever 280. The body of the wire in its passage to the tube extends between a pair of suitably-disposed feed wheels 288 the lower of which is 70 journaled on a stud shaft 289 projecting from the resilient supported arm 283 and the upper of which wheels is loose on the transverse shaft 273. Secured to and movable with the respective feed wheels 288 are intermeshing gears 290 by means 75

of which the feed wheels are concurrently rotated by actuation of the shaft 273, and secured also to the feed wheels are two friction wheels 292, the upper of which is peripherally flattened 5 or mutilated, as at 293. While the curved surfaces of the friction wheels are in contact the lower feed wheel is depressed against the resilient action of the arm 283 in a manner to free the wire from the bite of the feed wheels, but when 10 the mutilated surface of the upper friction wheel is in contact with the surface of the lower friction wheel the latter wheel is raised by the resilient action of the arm 283. Thus the wire is engaged by the two feed wheels and thereby intermittently advanced a limited distance to project 15 its free end beyond the cutter head and in the upward path of the moving mandrel. The projecting wire portion, which is equal to a wire length for the formation of a staple, overlies the 20 mandrel in the plane of the lower end of the staple former, such end being grooved for the passage of the projecting wire.

Fixed to the stationary block 241 is a vertical bar 294 having a depending cutter member 295 adjacent one side of the staple former and in close relation to the top of the beveled face of the perforated cutter member 278 so as to overhang the path of the projecting end of the wire. The member 295 is wedge-shaped in cross-section, its 30 beveled face corresponding with and being substantially in the vertical plane of the beveled face of the movable cutter member.

The cutter bearing end of the lever 280 rests upon one arm 296 of a bell crank which is fulcrumed on a bracket 297 in the housing 212, the other arm 298 of the bell crank having a roll 299 which is held in contact with a suitable cam 300 fast on the driven shaft 369. The contour of the cam 300 is such that at a determined interval the bell crank is actuated to effect the oscillation of the lever 280 and the cutter member 278, the beveled edge of which latter in its upward stroke co-acts with the opposing beveled edge of the fixed cutter member 295 to sever the projecting 45 end of the wire at an acute angle. (See Fig. 32.) The upward travel of the lever 280 is sufficient to raise the cutter member 278 above the path of the upper end of the reciprocating guide head 249 at the staple former 240, and the contour of the cam 300 is such as to maintain the cutter member thus elevated until the initial descent of the guide head. (See Fig. 27.) Thereupon the lever and associated cutter member resume their previous down position. Immediately the wire is 50 severed the mandrel in its upper orbital travel impinges against the opposing midportion of the wire length and carries it forcibly into the staple former, thus bending the wire into the form of a conventional staple which is securely yet slidably held in such former. In the continued orbital movement of the mandrel it recedes from the staple former and the staple preparatory to a similar forming action on the next succeeding wire length presented to the path of the mandrel.

When the staple has been formed and positioned in the staple former the inserting plunger 217 descends and drives the staple and the associated wisp of fibers through the guide head 249 and into a hole of the underlying brush block, 55 as previously explained.

In the initial downward movement of the plunger 217 the cutter lever 280 is positively lowered at proper intervals by the impact thereon of a depending finger 301 which is secured 60 at its upper end to the slide 241 and is slidably in

a lateral extension 302 of the stationary block 241 at the bottom of the vertical guideway 238 of the frame structure 155. (See Figs. 12 and 13.)

Pivoted at 303 on the outer face of the lever 280 is a vertically movable gravity finger 304 having a beveled forward edge 305 which overhangs the outwardly projecting portion of the wisp when the latter is supported by the wisp carrier in the upstanding throat of the guide head 249, such finger thus riding yieldingly upon 10 the opposing wisp of fibers or bristles and preventing the upward displacement of the wisp. The finger 304 has a tail portion in which is formed an arcuate slot 306 through which freely extends a lateral pin 307 on the lever 280, which 15 pin thus co-acting with the slot limits the vertical movement of the finger.

An oscillatory tuft casing 308 having a transverse axis adjacent the foot of the housing 212 is mounted to swing in a vertical arc toward and 20 from the brush block in timed relation to the vertical reciprocations of the inserting plunger 217 and the guide head 249. When the casing is in vertical position its vertical axis is in alignment with the plunger and the central passage 25 of the guide head, at which time the tapered lower end of the latter in its downward stroke enters the casing 308, as seen in Figs. 13 and 37, and the associated staple and tuft are driven through the casing and into the underlying hole in the brush 30 block. When the plunger and the guide head are raised to clear the body of the casing, the casing is swung to one side or the other from the vertical plane of the plunger, as seen in Figs. 1 and 12 and as indicated by dotted lines in Fig. 35 37. The casing is provided with end toes 309 effective to push out of the way of the entering tuft the previously inserted tuft irrespective of the direction of movement, to the right or the left, of the brush block (B) beneath the tuft 40 inserting plunger.

One side of the tuft casing has an upward extension 310 which is secured to the adjacent end of a transverse rock shaft 311 having its bearings in suitably-disposed brackets 312 on the 45 housing 212 (Figs. 34 and 35). On the remote end of the shaft 311 is a broad-faced gear 313 in mesh with an idler gear 314 which, in turn, meshes with a similar broad-faced gear 315, the gears 314 and 315 being loose on parallel stud 50 shafts 316 and 317, respectively, projecting from a vertical plate 318 secured to the outer face of the housing 212. Hence, when either of the gears 313 or 315 is partially rotated, clockwise or counterclockwise, the tuft casing is likewise 55 moved. Meshing with the gears 313 and 315 are two oppositely-disposed gear racks 319 and 320 respectively, which are formed on or secured to two parallel slide bars 321. The racks are supported in meshing relation with the opposing 60 gears 313 and 315 by a roll 322 on the lower stud shaft 316, while the opposite end portions of the bars 321 are slidably mounted one upon the other in a guide structure 323 which is supported by the housing 212. The opposing faces of the 65 two rack bars have therein correspondingly located notches 324 with either of which a laterally projecting pin 325 on the free end of a reciprocating arm 326 can be engaged when the notches are in register at the end of either stroke of 70 the arm, which arm thus independently moves the connected rack bar 321, and the latter transmits a rocking motion through the described gearing to the tuft casing. By virtue of the opposite relation of the rack bars to the respective 75

gear wheels 313 and 315, such bars are moved in opposite directions and the tuft casing is thereby swung from vertical to right or left oblique position, and the converse, as determined by 5 the stroke of the active bar.

The arm 326 is adjustably pivoted, as at 327, to the depending arm 328 of an angle lever fulcrumed on a bracket 329 on the beam 38 of the main frame, the other arm 330 of the 10 lever having a roll 331 which is operatively fitted in the groove of a suitable cam 332 on the driven shaft 140 previously referred to. The contour of the cam groove is such that the angle lever is periodically rocked on its axis and the arm 15 326 is thereby longitudinally reciprocated; that is to say, the cam groove has a concentric or dwell portion x which during a half rotation of the cam maintains the associated lever arm at rest, and has also reversely disposed elongation 20 portions y which oscillate the arm during the remainder of the rotation of the cam. (See Figs. 1, 34, 35, 36, and 37.)

As a means to rock the reciprocating arm 326 on its pivot 327 at determined intervals to engage the pin 325 with the notches 324 of the 25 bars 321 in alternation, the outer end of the pin is formed with a head 333 which travels between the legs 334 of a bifurcated cam lever 335 pivotally supported on the lower stud shaft 316. The inner face of the forward portion of the lower leg 334 is beveled, as at 336, to provide an inclined cam surface which by actuation of the lever 335 is periodically moved in respect to the longitudinal path of the pin head 333 during the operation of the arm 326. The 30 upper leg of the lever 335 is jointed, as at 337, to one of the upper arms 338 of a T-lever which is fulcrumed at 339 on one side of the standards of the main frame, the other upper arm 340 being jointed, as at 341, to a vertical cage 342 through which the upper end of a depending actuating rod 343 slidably extends. The portion of the rod 343 within the cage has a collar 344 fast thereon, and oppositely acting springs 345, 45 which encircle the rod, bear against the ends 346 of the cage and the respective opposing faces of the collar, thus providing a resilient coupling between the rod and the lever arm 340.

The lower end of the rod 343 is pivotally connected to one arm 347 of a bell-crank fulcrumed on one of the rearwardly extending arms 42 of the fixed cross-bar 43. The other arm 348 of the bell-crank has a roll 349 in the path of a series of tappet plates 350 which are adjustably fitted in 50 undercut guide slots 351 in bosses 352 on the face of the pattern cam wheel 45. The tappets 350 are disposed alternately in reversed angular relation as seen in Figs. 1 and 37, so as to act at intervals upon the opposing roll 349 in a manner to oscillate 55 the bell-crank, thereby through the resiliently coupled rod and lever connections effecting the vertical rocking of the bifurcated cam lever 338 in timed relation to the notched rack bars 321. (See Figs. 1, 5, 18 and 35.)

The co-operative relation of the various tuft casing actuating elements just described is such that when the cam controlled lever arm 330 and its connections are at rest and the tuft casing is in vertical position, as seen in Fig. 37, the guide head 249 and the inserting plunger 217 are jointly reciprocated through the tuft casing 308 toward and from the underlying brush block. At this stage the rack bars 321 are positioned with their 60 notches 324 in register, and the arm 326 is posi-

tioned with the pin 325 engaged with the notch of the upper rack bar.

Preparatory to the next succeeding tuft setting operation a tappet plate 350 of the wheel 45 engages and escapes the opposing roll 349 of the bell 5 crank, thus actuating the rod 343 to swing the T-lever and position the bifurcated lever 335 with its beveled leg 334 below the pin head 333 of the arm 326. Hence the upper leg of the lever 335 bears upon the pin head and depresses the adjacent end 10 of such lever in a manner to enter the pin 325 in the notch of the lower rack bar 321. Consequently when the arm 326 is reciprocated during 15 the active rotation of the cam 332 the lower rack bar 321 is moved rearward sufficiently to swing the tuft casing 308 to a forwardly inclined position in a manner to push back the opposing previously inserted tuft, and is then moved back so as to swing the casing to a vertical position, as seen in Fig. 31, preparatory to a succeeding reciprocation of the guide head 249 and the inserting plunger 217. At this juncture the arm 326 and its 20 connections are at rest, and the next succeeding tappet plate 350 on the intermittently moving wheel 45 engages and escapes the opposing roll of 25 the bell-crank 347, 348 to swing the T-lever in a direction reversely of its previous motion by the preceding tappet plate 350, thus slightly raising the bifurcated lever 335 and positioning its lower leg 334 in the path of the pin head 333 of the arm 30 326. Hence the lower leg of the lever 335 raises the pin from the notch of the lower rack bar 321 and engages it with the notch of the upper rack bar, which notches at this stage are in register. Hence when the arm 326 is reciprocated during 35 the active rotation of the cam 332 the upper rack bar is moved forward a limited distance to swing the tuft casing to a rearwardly inclined position in a manner to push away the opposing previously 40 inserted tuft, and which casing is then moved back to vertical position in operative relation to the path of the guide head 249 and the inserting plunger 217; and so on during the tuft setting operations the tuft casing is oscillated through the alternate operations of the two rack bars. 45

The depending arm 353 of the T-lever is formed with a foot 354 having two suitably spaced notches 355 and 356 therein with one or the other of which a laterally projecting pin 357 on a latch lever 358 is adapted yieldingly to engage during each 50 succeeding interval of rest of the T-lever when the tuft casing is in vertical position, thereby temporarily locking the latter. When the bifurcated lever 335 is depressed by the action thereon of the pin head 333, the T-lever is actuated to tilt 55 its depending arm 353 rearward, as in Fig. 37, thus disengaging the rearward foot notch 355 of the arm 353 from the spring pressed locking pin 357 and engaging the forward notch 356 with the latter, and when subsequently the bell-crank 347, 60 348 is actuated by a tappet 350 of the wheel 45 the T-lever is moved to tilt its arm 353 forward, thus disengaging the locking pin 357 from the notch 356 and engaging it with the notch 355 of the lever arm 353, as indicated by dotted lines 65 in Fig. 37. The latch lever 358, which underlies the foot of the notched arm 353, is pivoted at one of its ends to the main frame, the opposite end of the lever being resiliently supported by a suitably-disposed retracting spring 359. 70

The general operation of the machine may be briefly described as follows:

A brush block (B) is mounted on the table 49 beneath the boring tool 145 and the machine is then started by manual actuation of the crank 75

shaft 67. Thereupon and in the continued operation of the machine the various positions of the table to present the block progressively in proper relation to the actions of the boring tool, are effected through the described connections between the table and the intermittently rotating pattern cams. When the face of the brush block has been properly bored the machine is automatically stopped by the uncoupling of the cam 10 64 from the continuously driven pulley 40 on the main shaft 39. This done, the bored block is removed from the table 49 and an unbored block is substituted therefor. The previously bored block is positioned on the table 50 beneath the tuft setting device and the machine is again manually started, as before. In this succeeding operation the face of the brush block on the table 49 is bored while tufts are being progressively inserted in the holes of the block on the table 50. Upon 20 the completion of the boring and tuft setting operations the machine is automatically stopped, and the bored and filled blocks are manually removed from their respective tables; the bored block is positioned on the table 50 beneath the tuft inserting device and an unbored block is positioned on the table 49 beneath the boring tool. In the next succeeding operation of the machine one brush block is being bored while the other is being supplied with tufts. On the completion of this operation the machine is again automatically stopped. This done the filled and bored blocks are manually removed from their respective tables, the bored block is mounted on the table 50, and an unbored block on the table 35 49. The machine is again manually started, and the described boring and tuft setting operations are repeated; and so on.

In the operation of the tuft setting mechanism wisps of fibers are removed from the throat 156 40 of the magazine 152 by the oscillating transfer head and transferred thereby to and between the open jaws of the wisp carrier, which carrier at this juncture is at the limit of its forward stroke. As the transfer head returns to the magazine for 45 a succeeding wisp of fibers the wisp carrier moves rearward and positions the wisp across the downward path of the elevated inserting plunger 217 and directly over the throat of the guide head 249, which latter at this time has a slight dwell 50 in its upward travel. During this period a wire end is fed to and positioned across the upward path of the mandrel 264 at the nose of the staple former 240 by means of the intermittently acting wire feed devices, such end is severed from 55 the body of the wire by means of the co-acting cutters 278 and 279, and the severed end, by the action thereon of the mandrel in its upward orbital travel, is forced into the opposing staple former and thereby formed into a staple (S) 60 which is positioned below the elevated plunger. Thereupon as the guide head 249 completes its upward travel the throat of the head receives the wisp which is supported on the wisp carrier and moves to a position in close relation to the 65 nose of the staple former. Immediately thereafter the plunger, descending, forces the staple from the staple former and into the throat of the guide head so as to straddle the midportion of the opposing wisp. In the continued descent of the plunger the associated staple and wisp are 70 driven down through and beyond the wisp folding passage of the guide head, thus doubling the wisp into tuft form and driving the staple and tuft down into the underlying hole in the brush block. In the down stroke of the inserting 75

plunger the guide head is actuated by its connections with the cam 246 to move in timed relation with the plunger to the brush block, and upon the completion of the tuft setting operation said plunger and guide head are raised and relatively positioned for a similar tuft setting operation in respect to the next succeeding hole of the brush block. 5

As the tapering lower end of the guide head 249 approaches the brush block the tuft casing 308 is 10 in vertical position to permit the free passage of the tuft holder and the plunger. This casing, by virtue of the motion transmitting connections which are actuated by the tappets 359 on the wheel 45, is alternately moved from vertical to 15 inclined positions at determined intervals in a manner to push back adjacent previously inserted tufts in the brush block.

It is to be understood that my invention is not limited to the particular construction disclosed, 20 as the mechanisms may be modified within the principle of the invention and the scope of the appended claims.

I claim—

1. In a brush machine having means for supporting a brush block and having also a staple and tuft inserting plunger reciprocative toward and from the brush block support, a stationary staple former through which the plunger reciprocates, means for shaping and positioning a 25 staple in said staple former, means for positioning a wisp of fibers below said staple former and across the path of the plunger, a reciprocative guide element mounted below the said staple former and operative in its stroke toward the 30 former to move in close relation to the former the wisp positioned therebelow, said guide element having an axial alignment with the staple former and the plunger, a passage which receives the plunger, the staple and the wisp during 35 the down or active stroke of the plunger, and means for reciprocating said plunger and guide element in timed relation to each other and to the wisp positioning and staple shaping means. 40

2. In a brush machine having means for supporting a brush block and having also a staple and tuft inserting plunger reciprocative toward and from the brush block support, a fixed staple former, means for shaping and positioning a 45 staple in said staple former, means for positioning a wisp of fibers below said staple former and across the path of the plunger, a reciprocative guide element mounted below the said staple former and comprising a body having an 50 upstanding throat portion leading to a lower wisp doubling passage, whereby said throat portion receives the wisp while the guide element is moving to a position in proximity to the staple former and whereby in the down or active stroke of the plunger the staple is pushed by the plunger into 55 and through the said throat portion so as to straddle the wisp and force it down into and through the passage of the guide element, and means for reciprocating said plunger and guide element in timed relation to each other and to the wisp positioning and staple shaping means. 60

3. In a brush machine having means for supporting a brush block and having also a staple and tuft inserting plunger reciprocative toward and from the brush block, a stationary staple former through which the plunger reciprocates, means for shaping and positioning a staple in 70 said staple former and comprising a mandrel movable under, into and from the staple former, means for intermittently projecting the free end 75

of a wire across said mandrel when the mandrel is under the staple former, and means for severing the projecting end of the wire preparatory to the movement of the mandrel into the staple former, means for positioning a wisp of fibers below said staple former and across the path of the plunger, a reciprocative guide element mounted below the said staple former and operative in its stroke toward the former to move in close relation to the former the wisp positioned therebelow, said guide element having an axial alignment with the staple former and the plunger a passage which receives the plunger, the staple and the wisp during the down or active stroke of the plunger, and means for reciprocating said plunger and guide element in timed relation to each other and to the wisp positioning and staple shaping means.

4. In a brush machine having means for supporting a brush block and having also a staple and tuft inserting plunger reciprocative toward and from the brush block support, a stationary staple former through which the plunger reciprocates, means for shaping and positioning a staple in said staple former and comprising a mandrel movable in a vertical orbital path from a position under, into and from the staple former, means for intermittently projecting the free end of a wire across said mandrel when the mandrel is under the staple former, and means including complementary fixed and movable cutters for severing the projecting end of the wire preparatory to the movement of the mandrel into the staple former, means for positioning a wisp of fibers below said staple former and across the path of the plunger, a reciprocative guide element mounted below the said staple former and operative in its stroke toward the former to move in close relation to the former the wisp positioned therebelow, said guide element having an axial alignment with the staple former and the plunger a passage which receives the plunger, the staple and the wisp during the down or active stroke of the plunger, and means for reciprocating said plunger and guide element in timed relation to each other and to the wisp positioning and staple shaping means.

5. In a brush machine having means for supporting a brush block and having also a staple and tuft inserting plunger reciprocative toward and from the brush block support, a fixed staple former through which the plunger reciprocates, means for shaping and positioning a staple in said staple former and comprising a mandrel movable in a vertical path from a position under, into and from the staple former, means for intermittently projecting the free end of a wire across said mandrel when the mandrel is under the staple former, and means, including co-acting fixed and movable cutter members, for severing the projecting end of the wire preparatory to the movement of the mandrel into the staple former, means for positioning a wisp of fibers below said staple former and across the path of the plunger, and a reciprocative guide element mounted below the said staple former and comprising a body having an upstanding throat portion leading to a lower wisp doubling passage, whereby said throat portion receives the wisp while the guide element is moving to a position in proximity to the staple former and whereby in the down or active stroke of the plunger the staple is pushed by the plunger into and through said throat portion so as to straddle the wisp and force it down into and through the passage of the guide element.

ment, and means for reciprocating said plunger and guide element in timed relation to each other and to the wisp positioning and staple shaping means.

6. In a brush machine having means for supporting a brush block and having also a staple and tuft inserting plunger reciprocative toward and from the brush block support, a fixed staple former through which the plunger reciprocates, means for shaping and positioning a staple in said staple former and comprising a mandrel movable in a vertical path from a position under, into and from the staple former, means for intermittently projecting the free end of a wire across said mandrel when the mandrel is under the staple former, and means including a depending fixed cutter member adjacent the staple former, a vertically movable cutter member co-acting with the fixed cutter member to sever the projecting end of the wire preparatory to the movement of the mandrel into the staple former, and means for raising said movable cutter member in its active stroke above the nose of the staple former, means for positioning a wisp of fibers below said staple former and across the path of the plunger, and a reciprocative guide element mounted below the said staple former and comprising a body having an upstanding throat portion leading to a lower wisp doubling passage, whereby said throat portion receives the wisp while the guide element is moving to a position in proximity to the staple former and whereby in the down or active stroke of the plunger the staple is pushed by the plunger into and through said throat portion so as to straddle the wisp and force it down into and through the passage of the guide element, and means for reciprocating said plunger and guide element in timed relation to each other and to the wisp positioning and staple shaping means.

7. In a brush machine having fiber supply means, means for supporting a brush block, and a staple and tuft inserting plunger reciprocative toward and from the brush block support, a stationary staple former through which the plunger reciprocates, means for shaping and positioning a staple in said staple former, a wisp carrier movable toward and from the path of the plunger below the staple former, a fiber transfer element movable between the fiber supply means and the wisp carrier and operative to transfer succeeding wisps of fibers from the supply means to the carrier, means for actuating said transfer element, wisp carrier and plunger in co-operative relation, and a reciprocative guide element mounted below the said staple former and operative in its stroke toward the former to move in close relation to the former the wisp positioned therebelow, said guide element having an axial alignment with the staple former and the plunger a passage which receives the plunger, the staple and wisp during the down or active stroke of the plunger, and means for reciprocating said plunger and guide element in timed relation to each other and to the transfer element, the carrier and the staple shaping means.

8. In a brush machine having means for supporting a brush block and having also a staple and tuft inserting plunger reciprocative toward and from the brush block support, a stationary staple former through which the plunger reciprocates, means for shaping and positioning a staple in said staple former, means for position-

ing a wisp of fibers below said staple former and across the path of the plunger, and a reciprocative guide element mounted below the said staple former and operative in its stroke toward the former to move in close relation to the former the wisp positioned therebelow, said guide element having an axial alignment with the staple former and the plunger a passage which receives the plunger, the staple and the wisp during the down or active stroke of the plunger, an oscillatory tuft casing mounted adjacent the brush block and periodically movable to and from the lower path of the guide element and the plunger, and means for reciprocating said plunger and guide element in timed relation to each other, the wisp positioning and stapling means and the tuft casing.

9. In a brush machine having a brush block support, fiber supply means, and a plunger reciprocative toward and from said support, the combination of a stationary staple former through which the plunger reciprocates, means for shaping and positioning a staple in said staple former, a wisp carrier movable toward and from the active path of the said plunger below said former, a fiber transfer element movable between the fiber supply means and the wisp carrier and operative to transfer succeeding wisps of fibers from the supply means to the carrier, means for moving said transfer element and wisp carrier toward and from each other in such timed relation that the transfer element is in position to receive a wisp from the supply means while the carrier is presenting to the path of the plunger the last preceding wisp which was delivered to the carrier by said transfer element, a reciprocative guide element mounted below the said staple former and operative in its stroke toward the former to move in close relation to the former the wisp positioned therebelow, said guide element having in axial alignment with the staple former and the plunger a passage which receives the plunger, the staple and the wisp during the active stroke of the plunger, and means for reciprocating said plunger and guide element in timed relation to each other and to the staple shaping means, the transfer element and the wisp carrier.

10. In a brush machine having a brush block support, fiber supply means, and a plunger reciprocative toward and from said support, the combination of a stationary staple former through which the plunger reciprocates, means for shaping and positioning a staple in said staple former, a reciprocating wisp carrier movable in an upwardly inclined path toward and from the active path of the said plunger below said former, an oscillatory fiber transfer element movable between the fiber supply means and the wisp carrier and operative to transfer succeeding wisps of fibers from the supply means to the carrier, means for moving said transfer element and wisp carrier toward and from each other in such timed relation that the transfer element is in position to receive a wisp from the supply means while the carrier is presenting to the path of the plunger the last preceding wisp which was delivered to the carrier by said transfer element, a reciprocative guide element mounted below the said staple former and operative in its stroke toward the former to move in close relation to the former the wisp positioned therebelow, said guide element having in axial alignment with the staple former and the plunger a passage

which receives the plunger, the staple and the wisp during the active stroke of the plunger, and means for reciprocating said plunger and guide element in timed relation to each other and to the staple shaping means, the transfer element and the wisp carrier.

11. In a brush machine having a brush block support, fiber supply means, and a plunger reciprocative toward and from said support, the combination of a wisp carrier movable toward and from the active path of the said plunger, and comprising a reciprocative frame structure having normally closed clamping jaws, and means for opening said jaws at the end of each outward stroke of the said structure, a fiber transfer element movable between the fiber supply means and the said structure and operative to transfer succeeding wisps of fibers from the supply means to and between the open jaws of said structure immediately preceding the return stroke of the structure and the closing of the jaws, and means for moving said transfer element and wisp carrier toward and from each other in such timed relation that the transfer element is in position to receive a wisp from the supply means while the carrier is presenting to the path of the plunger the last preceding wisp which was delivered to the carrier by said transfer element.

12. In a brush machine having a brush block support, fiber supply means, and a plunger reciprocative toward and from said support, the combination of a fixed guide member for the said plunger, a wisp carrier movable toward and from the active path of the carrier below said guide member, a fiber transfer element movable between the fiber supply means and the wisp carrier and operative to transfer succeeding wisps of fibers from the supply means to the carrier, a reciprocative guide head adapted to receive the wisp from the carrier and having a vertical guide passage for the wisp and the plunger, means for moving said transfer element and wisp carrier toward and from each other in such timed relation that the transfer element is in position to receive a wisp from the supply means while the carrier is presenting to the path of the plunger the last preceding wisp which was delivered to the carrier by said transfer element, and means for reciprocating said guide head in timed relation to the carrier, the transfer element and the plunger.

13. In a brush machine, the combination of a plunger, a fixed guide therefor having a bifurcated nose portion constituting a staple former, means for forming and positioning a staple in said former, a reciprocative guide head movable toward and from said former, said former having a centrally slotted upper portion and a lower wisp folding passage, means for positioning a wisp of fibers below the said former and across the path of the guide head, whereby in the upward stroke of the guide head its upper slotted portion receives and embraces said wisp, and whereby in the downward stroke of the plunger the staple is forced from the said former and into the slot of the guide head so as to straddle the said wisp and carry it therewith into and through the folding passage of the guide head, and means for reciprocating said guide head and plunger in timed relation to each other and to the wisp positioning and staple forming means.

14. In a brush machine having a brush block support, fiber supply means, and a plunger reciprocative toward and from said support, of a wisp carrier having a wisp support movable to

ward and from the active path of said plunger, a fiber transfer element movable between the fiber supply means and the wisp carrier and operative to transfer succeeding wisps of fibers from the 5 supply means to the carrier, means for moving said transfer element and wisp carrier in co-operative relation, a guide head having a central passage in the active path of the plunger, and means for reciprocating said guide head longitudinally 10 of said path and in timed relation to the wisp carrier and the plunger, whereby the wisp is positioned by the carrier in the path of the guide head and the plunger, whereby the plunger in its stroke toward the brush block support forces 15 the wisp through and folds it in the passage of the guide head, and whereby said guide head moves with the plunger toward the brush block support.

15. In a brush machine, the combination of a 20 stationary element constituting a staple former, a reciprocating plunger guided in and longitudinally of said element, a wisp carrier movable toward and from the path of the plunger, a movable guide head mounted below said former and having 25 a central passage in the path of the plunger, and means for reciprocating said guide head longitudinally of said path and in timed relation to the wisp carrier and the plunger, whereby the wisp is positioned by the carrier below and spaced 30 from the staple former and across the path of the guide head, whereby the plunger in its active stroke forces the staple and the wisp through and folds the wisp in the passage of the guide head, and whereby said guide head moves with the 35 plunger during the active stroke of the latter.

16. In a brush machine, the combination with a stationary element having a bifurcated nose portion constituting a staple former, a reciprocating plunger in said element, and means for shaping 40 and positioning a staple in said staple former, of a wisp carrier movable toward and from the path of the plunger, a movable guide head having a passage in the path of the plunger, and means for reciprocating said guide head longitudinally 45 of said path and in timed relation to the wisp carrier and the plunger, whereby the wisp is positioned by the carrier in the path of the guide head and the plunger, whereby the plunger in its active stroke forces the wisp through and folds it in the 50 passage of the guide head, and whereby said guide head moves with the plunger during the active stroke of the latter.

17. In a brush machine having means for supporting a brush block and having also a staple 55 and tuft inserting plunger reciprocative toward and from the brush support, a stationary staple former through which the plunger reciprocates, means for positioning a wisp of fiber below said staple former and across the path of the plunger, 60 a mandrel movable under, into and from the staple former through a determined continuous path, means for actuating said mandrel in timed relation to the plunger, means for intermittently projecting the free end of a wire across said mandrel when the mandrel is under the staple former, 65 and means for severing the projecting end of the wire preparatory to the movement of the mandrel into the staple former, whereby in the entrant travel of the mandrel the severed wire is carried 70 into the stationary staple former and therein bent to staple form.

18. In a brush machine having means for supporting a brush block and having also a staple 75 and tuft inserting plunger reciprocative toward and from the brush support, a stationary staple

former through which the plunger reciprocates, means for positioning a wisp of fiber below said staple former and across the path of the plunger, a mandrel movable in a vertical orbital path under, into and from the staple former, means for actuating said mandrel in timed relation to the plunger, means for intermittently projecting the free end of the wire across said mandrel when the mandrel is under the staple former, and means for severing the projecting end of the wire preparatory to the movement of the mandrel into the staple former, whereby in the entrant travel of the mandrel the severed wire is carried 10 into the stationary staple former and therein bent to staple form. 15

19. In a brush machine having means for supporting a brush block and having also a staple and tuft inserting plunger reciprocative toward and from the brush support, a stationary staple former through which the plunger reciprocates, 20 means for positioning a wisp of fiber below said staple former and across the path of the plunger, a mandrel movable under, into and from the staple former through a determined continuous path, means for actuating said mandrel in timed 25 relation to the plunger, means for intermittently projecting the free end of a wire across said mandrel when the mandrel is under the staple former, and means for severing the projecting end of the wire preparatory to the movement of the 30 mandrel into the staple former, whereby in the entrant travel of the mandrel the severed wire is carried into the stationary staple former and therein bent to staple form, said last named means including co-acting fixed and movable 35 cutter members adjacent the staple former, and means for actuating the movable cutter member.

20. In a brush machine having means for supporting a brush block and having also a staple and tuft inserting plunger reciprocative toward 40 and from the brush support, a stationary staple former through which the plunger reciprocates, means for positioning a wisp of fiber below said staple former and across the path of the plunger, a mandrel movable under, into and from the staple 45 former through a determined continuous path, means for actuating said mandrel in timed relation to the plunger, means for intermittently projecting the free end of a wire across said mandrel when the mandrel is under the staple 50 former, and means for severing the projecting end of the wire preparatory to the movement of the mandrel into the staple former, whereby in the entrant travel of the mandrel the severed wire is carried into the stationary staple former and therein bent to staple form, said last named means including co-acting fixed and movable 55 cutter members adjacent the staple former, and means including a bell crank and cam for actuating the movable cutter member. 60

21. In a brush machine, a fiber containing magazine having a discharge throat, a transfer element for removing succeeding wisps of fibers from said throat, end evening means including a vibratable plate for acting against the ends of the fibers within the magazine adjacent said throat, means including a transverse pusher member for feeding the contained fibers toward said throat and into the transfer element, and means for simultaneously actuating said evening and 65 feeding means.

22. In a brush machine, a fiber containing magazine having a discharge throat, a transfer element for removing succeeding wisps of fibers from said throat, end evening means for the fibers at 70

- the throat, said evening means including a presser member and a vibratory supporting arm therefor, means for feeding the contained fibers toward said throat and into the transfer element, said feeding means including a pusher member and a vibratory supporting arm therefor, means for vibrating one of said arms, and co-acting means on the respective arms for transmitting motion from the vibrated arm to the other arm. 5
23. In a brush machine, a brush block supporting table, means including pattern cam elements and motion transmitting devices co-acting with said cam elements to impart co-ordinated vertical, longitudinal and transverse rocking movements, respectively, to said table, the transmitting devices for imparting the transverse rocking movements to the table including a lever, a stabilizing arm to one end of which said lever is pivoted, said end having an actuating portion 10 in operative contact with one of the pattern cam elements, and a stationary control cam for the other end of the arm. 15
24. In a brush machine, a brush block supporting table, means including pattern cam elements and motion transmitting devices co-acting with said cam elements to impart co-ordinated vertical, longitudinal and transverse rocking movements, respectively, to said table, the transmitting devices for imparting the transverse rocking movements to the table including resilient means normally urging the table in one lateral direction, a slidably mounted transverse shaft, means tending to retract the shaft in opposition to the action of one of the cam elements, operative connections between said shaft and such cam element, a shifter arm pivotally connected with but movable with said shaft, said arm having at its free end a lateral projection, and a bar operatively connected with the said table and having a socketed portion which is resiliently held in contact with the projection of the said shifter arm. 20
25. In a brush machine having spaced boring and tuft inserting mechanisms, two pivotally supported brush block supporting tables arranged in co-operative relation to the respective mechanisms, a pivotally supported table between the block supporting tables, a perforated centering plate arranged on said table in co-operative relation to the centering pin, and means including pattern cam elements and motion transmitting devices co-acting with said cam elements to impart co-ordinated vertical, longitudinal and transverse rocking movements, respectively, to said tables, the transmitting devices for imparting the transverse rocking movements to the tables including coupling means for 25 said tables, resilient means normally urging the tables in one lateral direction, a slidably mounted transverse shaft, means tending to retract the said shaft in opposition to the action of one of the cam elements, operative connections between said shaft and such cam element, an arm loose on but movable with said shaft, a shifter arm pivoted on said other arm and having at its free end a lateral projection, and a bar connected with said coupling means and having a socketed portion which is resiliently held in contact with the projection of the said shifter arm. 30
26. In a brush machine having spaced boring and tuft inserting mechanisms, two pivotally supported brush block supporting tables arranged in co-operative relation to the respective mechanisms, a pivotally supported table between the block supporting tables, a perforated centering plate arranged on said table in co-operative relation to the centering pin, and means including pattern cam elements and motion transmitting devices co-acting with said cam elements to impart co-ordinated vertical, longitudinal and transverse rocking movements, respectively, to said tables, the transmitting devices for imparting the transverse rocking movements to the tables including coupling means for 35 said tables, resilient means normally urging the tables in one lateral direction, a slidably mounted transverse shaft, means tending to retract the said shaft in opposition to the action of one of the cam elements, operative connections between said shaft and such cam element, an arm loose on but movable with said shaft, a shifter arm pivoted on said other arm and having at its free end a lateral projection, and a bar connected with said coupling means and having a socketed portion which is resiliently held in contact with the projection of the said shifter arm. 40
25. In a brush machine having spaced boring and tuft inserting mechanisms, two pivotally supported brush block supporting tables arranged in co-operative relation to the respective mechanisms, and means including pattern cam elements and motion transmitting devices co- 45

WILLIAM D. LIPPS.

CERTIFICATE OF CORRECTION.

Patent No. 2,097,296.

October 26, 1937.

WILLIAM D. LIPPS.

It is hereby certified that error appears in the printed specification of the above numbered patent requiring correction as follows: Page 9, second column, line 38; page 10, first column, lines 11 and 40; same page, second column, line 61; and page 11, first column, line 7; claims 1, 3, 4, 7, and 8, for the word "an" read in; page 9, second column, line 39, claim 1, strike out the comma after "plunger"; and that the said Letters Patent should be read with these corrections therein that the same may conform to the record of the case in the Patent Office.

Signed and sealed this 7th day of December, A. D. 1937.

Henry Van Arsdale,
Acting Commissioner of Patents.
